UNITED STATES PATENT OFFICE.

SOLOMON MEYERS, OF OLYMPIA, WASHINGTON, ASSIGNOR TO OLYMPIA KNITTING MILLS, INC., OF OLYMPIA, WASHINGTON, A CORPORATION OF WASHINGTON.

DESIGN FOR A MUFFLER.

41,905.

Specification for Design.

Patented Nov. 7, 1911.

Application filed November 14, 1910. Serial No. 592,411. Term of patent 14 years.

To all whom it may concern:

Be it known that I, SOLOMON MEYERS, a citizen of the United States, residing at Olympia, in the county of Thurston and State of Washington, have invented a new, original, and ornamental Design for Mufflers, of which the following is a specification.

Reference is had to the accompanying drawing, in which:—

Figure 1 is a plan view of a muffler, showing my new design. Fig. 2 is a front elevation of the muffler. Fig. 3 is a rear elevation of the same.

The design is characterized by two ornamental straight end portions 1 and an ornamental zig-zag neck portion 2. The ornamental end portions 1 are in substantial alinement, and the neck portion consists of a se-

ries of spaced diagonally arranged rhomboidal portions 3, and straight oblong connecting portions 4 and 5, arranged between the rhomboidal portions in staggered relation. The oblong portion 5 is located at the center of the neck portion and is of a width slightly in excess of the oblong portions 4, which are arranged at opposite sides of the center of the neck portion.

I claim:

The ornamental design for a muffler, as shown and described.

In testimony, that I claim the foregoing as my own, I have hereto affixed my signature in the presence of two witnesses.

SOLOMON MEYERS.

Witnesses:

J. M. STEELE,
CHARLES O. PARKS.

Copies of this patent may be obtained for five cents each, by addressing the "Commissioner of Patents, Washington, D. C."
